UNITED STATES PATENT OFFICE

2,581,777

COMBINATION CONNECTING AND STABILIZING BAR FOR MASONRY SAWS

Harold J. Wright, Kansas City, Mo., assignor to
Clipper Manufacturing Company, Kansas City,
Mo., a corporation of Missouri

Application November 8, 1948, Serial No. 58,837

2 Claims. (Cl. 125—13)

1

This invention relates to masonry saws of the type having a cutter head mounted for swinging movement on a substantially horizontal axis, the head being provided with a rotatable cutter disc at one end thereof.

One of the primary aims of this invention is to improve upon the masonry saws forming the subject matter of U. S. Letters Patent Numbers 2,171,024, dated August 29, 1939, 2,338,318, dated January 4, 1944, and 2,450,371, dated September 28, 1948, and more particularly to bring together in a new combination certain advantageous features of Patents 2,171,024 and 2,450,371.

In Patent No. 2,450,371, there is disclosed novel means for permitting simple adjustment of the cutter head, forming a part of a masonry saw, to selected positions with respect to the vertical, including a fulcrum arm connected to the cutter head and serving as a support for the cutter head as shifting movement is imparted thereto. The entire assembly of this last mentioned patent has proved quite satisfactory but is disadvantageous when placed in use because of the fact that the foot operated mechanism for swinging the cutter head as a unit on its horizontal axis as disclosed in Pat. No. 2,171,024, was entirely eliminated.

Accordingly, it is the most important object of this invention to provide a stabilizing means for supporting the cutter head with the cutter thereof in a given position, together with a foot operated actuating means for swinging the cutter to and from a position in operative engagement with the work being handled whenever the stabilizing means is in a released position.

Another important object of this invention is the provision of a masonry saw having a cutter head that is swingably mounted on a horizontal axis and provided with a depending member that is in turn connected with manually operable mechanism for reciprocating the same and thereby swinging the cutter head on its pivotal axis, the depending member being provided with a manually releasable clamping assembly for holding the member against reciprocable movement when it is desired to hold the cutter in a selected position.

A further object of the present invention is the provision of a masonry saw of the above mentioned character wherein the vertically reciprocable rod depending from the cutter head is operably interconnected with a manually shiftable lever through the medium of a collar slidably mounted upon the rod and having manually releasable structure for selectively inter-

2

connecting the sleeve and the rod at a number of positions on the latter.

A still further object of this invention is the provision of a masonry saw as above set forth 5 wherein the aforesaid slidable sleeve and its mounting assembly is adapted to serve as a fulcrum support for the upright rod that is connected to the cutter head, to the end that the latter may be shifted to various positions with 10 respect to the vertical and upon the supporting stand therefor.

Other more minor objects including details of construction will be made clear or become apparent as the following specification progresses, 15 reference being had to the accompanying drawing, wherein:

Fig. 1 is a side elevational view of a masonry saw having a combination connecting and stabilizing bar made in accordance with the present 20 invention, parts being broken away and in irregular cross section to reveal details of construction.

Fig. 2 is an enlarged, fragmentary, vertical cross - sectional view through the stabilizing 25 means for the masonry saw.

Fig. 3 is a fragmentary, detailed cross-sectional view taken on irregular line III—III of Fig. 2, looking in the direction of the arrows; and

Fig. 4 is a fragmentary, detailed, cross-sectional view taken on line IV—IV of Fig. 2.

In Fig. 1 of the drawing, there is shown a masonry saw having a stand broadly designated by the numeral 10, that includes a pair of upright front legs 12 and a pair of relatively long legs 14 that are interconnected by a horizontal tank 16 disposed adjacent the uppermost ends of the front legs 12.

Each leg 12 of the stand 10 is in turn joined 40 with a corresponding leg 14 through the medium of a horizontal brace member 18. It is noted that the legs 14 of the stand 10, are appreciably longer than the front legs 12 thereof, the uppermost ends of legs 14 being provided with a plurality of notches 22 that extend downwardly and inwardly from the normally foremost edge thereof.

A cutter head, broadly designated by the numeral 24, is disposed between the uppermost ends 50 of the rear legs 14, said cutter head 24 being provided with a platform 26 having a pair of opposed pintles 28, one only of which is illustrated in Fig. 1 of the drawing, that are slidably fitted into opposed notches 22 of the pair of legs 14. It is noted that the outwardly extending pintles 28

on the platform 26 are disposed intermediate the ends of the platform 26 at a point substantially balancing the entire cutter head 24 when the remaining component parts thereof are attached thereto. Such parts include a disc 30 rotatably mounted upon the platform 26 directly above the tank 16 and an electric motor 32 mounted upon the uppermost face of platform 26 at the opposite end thereof. Rotative motion is imparted to the cutter disc 30 from the motor 32 by means of a belt or the like 34.

An elongated tubular member 36 depends from that end of the platform 26 adjacent the motor 32, the uppermost end of the member 36 being pivotally connected to the platform 26 as at 38. The lowermost end of the tubular member 36 terminates in spaced relationship to the supporting surface for the stand 10 and extends downwardly between a pair of spaced jaws 40 and 42. These jaws 40 and 42 are both disposed between a pair of spaced apart arms 44 that extend outwardly and downwardly from the rearmost end of the stand 10 adjacent the legs 14 thereof. A pivot pin 46 interconnects the arms 44 near the outermost free ends thereof for pivotally receiving the jaw 40. Both of the jaws 40 and 42 have the faces thereof next adjacent the member 36 contoured arcuately to conform to the contour of the tubular member 36 and the jaw 42 is mounted upon a horizontal rod 48, disposed immediately below the tank 16.

The jaw 42 has an internally tapped bore 50 formed therethrough for intermeshing with external threads 52 formed on the proximal end of the rod 48. That end of the rod 48 opposite to the threads 52 thereof terminates adjacent the front of the machine forwardly of legs 12 thereof after first passing through an opening 54 formed in bracket 56. Manual rotative motion is imparted to the rod 48 through the medium of a crank 58 secured to the rod 48 adjacent this forwardmost end thereof.

A cross bar 60 interconnects the arms 44 intermediate the ends thereof and is provided with an opening 62 for rotatably supporting the shaft 48 adjacent the threads 52 thereof.

A pair of collars 64 and 66 are releasably secured to the rod 48, said collars 64 and 66 being on opposite sides of the cross bar 60 to prevent longitudinal reciprocation of the latter. It is thus far clear that rotative movement of the rod 48 in one direction through manipulation of the handle 58 will move the jaw 42 against the vertical tubular member 36 to clamp the same against the jaw 40 and thereby hold the member 36 against reciprocative movement on its longitudinal axis. Conversely, rotation of the rod 48 in the opposite direction will release the jaw 42 moving the same in the direction away from member 36 and toward the collar 64 whereby the member 36 is free to reciprocate longitudinally and swing on the pivotal point 38.

A sleeve 70 slidably mounted upon tubular member 36 below the lowermost jaw 40 has a laterally extending tube 72 thereon that is in register with sleeve 70 at the innermost end thereof.

A flexible cable 76 has one end thereof threaded into the outermost end of a plunger 78 that is in turn telescoped within tube 72. Plunger 78 slides in an opening formed in the free end wall of tube 72 and has an out-turned flange 79 thereon bearing against member 36.

One end of the plunger 78 extends through one of a plurality of openings 80 formed in the

tube 36. These openings 80 extend for a considerable distance along the tubular member 36 in a relatively straight line as clearly illustrated in Figs. 1 and 2 of the drawing. The extent of movement of plunger 78 into the member 36 is controlled by the flange 79 and a spring 82 is coiled about plunger 78 for holding the latter biased against the member 36.

Assembly of plunger 78 into tube 72 is through an opening 83 formed in sleeve 70 in opposed co-axial relationship to tube 72.

Longitudinal sliding movement of plunger 78 within the tube 72 is accomplished manually through the medium of a knob 84 on that end of cable 76 adjacent the bracket 56. Cable 76 is slidably mounted in a sleeve 86 held in position in bracket 56 by opposed lock nuts 88.

An elongated lever 94 is pivotally mounted intermediate the ends thereof upon a shaft 96 interconnecting the legs 14 below tank 16, the ends of lever 94 being bifurcated for pivotally receiving the sleeve 70 through the medium of a pair of opposed pintles 98 in the manner illustrated in Fig. 4 of the drawing.

Pintles 98 are shouldered intermediate their ends and a lock washer 99 between such shoulder and sleeve 70 holds pintles 98 threaded in sleeve 70 and permits free relative movement between sleeve 70 and lever 94.

A relatively short link 100 has a spring 102 coiled upon the uppermost end thereof that is interposed between a wing nut 104 threaded upon the link 100 and a fitting 106 intermediate the ends of the link 100 and slidably freely thereon. A shoulder (not shown) is formed on the link 100 to limit the extent of downward sliding movement of fitting 106 on the link 100. The substantially horizontal lever 94 is joined to the fitting 106 through the medium of a pair of opposed pintles in much the same manner as illustrated in Fig. 4 of the drawing, one of such pintles being designated and shown by the numeral 108. The lowermost end of the link 100 is pivotally connected as at 110 to an elongated bar 112 intermediate the ends of the latter.

One end of the bar 112 is pivotally connected to the legs 14 through the medium of a shaft 114 that interconnects said rear legs 14. The opposite free end of the bar 112 terminates in a foot pedal 116. Bar 112 is yieldably held at the uppermost end of its path of travel through the medium of a spring 118 that has one end thereof connected directly to the bar 112 and the opposite end joined to a bracket 120 secured to bracing members 18. The extent of upward movement of the bar 112 is limited by a rod 122 that depends from a cross brace (not shown) that interconnects the braces 18 intermediate the ends of the latter.

The open top tank 16 is designed for a cooling liquid, the means for directing such liquid to the cutter disc 30 forming no part of this invention and, therefore, need not be described. The uppermost longitudinal edges of the tank 16 carry a reciprocable work-receiving table 124 through the medium of rollers 126 that ride directly upon such edges.

Assuming the cutter head 24 to be positioned as illustrated in Fig. 1 of the drawing with the pintles 28 thereof disposed within opposed notches 22, the operation is as follows:

When the rod 48 is rotated to the position for releasing the jaws 40 and 42, the tubular member 36 is freely reciprocable therebetween and, therefore, foot pressure imparted to the bar 112

will cause corresponding swinging movement of the cutter head 24 on the pintles 28. Downward movement of bar 112 against the action of spring 118 will accordingly swing the lever 94 on its pivotal axis 96 through the link 100. As the lever 94 so swings, member 36 will be shifted upwardly because of the interconnection between member 36 and lever 94 by means of sleeve 70.

As the cutter 30 is thus moved toward and away from the work carried by the table 124, the latter is moved along the table 16 to and from a position where the cutter 30 will engage such work. The cutter 30 may be shifted nearer the table 124 than that illustrated in Fig. 1 of the drawing with the bar 112 in the normal inoperative position by the simple expedient of withdrawing the plunger 78 to permit free sliding movement of sleeve 70 upon member 36. Sleeve 70 is then moved downwardly upon member 36 and the cable 76 released, permitting plunger 78 to enter another of the holes 80.

In the event that the operator is desirous of rigidly positioning the cutter 30 at a predetermined distance above the table 24, the raising and lowering mechanism for the member 36 is not utilized. Instead, the rod 48 is rotated to bring the jaws 40 and 42 into tight clamping relationship with the member 36.

When it becomes necessary to raise or lower the cutter head 24 with respect to the rear legs 14 by moving the pintles 28 from one pair of notches to another pair of notches 22, the jaws 40 and 42 are released and the cutter head 24 lifted from the notches 22 while the rearmost end of the platform 26 rests upon the member 36. The opposed pintles 98, supporting sleeve 70 will, thereupon serve as a fulcrum and permit swinging movement of the member 36 toward the jaw 42 as the pintles 28 are slipped from notches 22.

Before such adjustment of the cutter head 24 is to be made with respect to the legs 14, the sleeve 70 can be positioned at the most desirable point on member 36 to facilitate movement of the cutter head 24. Inasmuch as the jaw 42 moves toward the stand 10 when releasing action takes place, the swinging movement of member 36 as aforesaid, can take place.

When jaw 42 is in the fully retracted position, the threaded end of rod 48 determines the swinging limit of member 36, which is sufficient to permit changing of pintles 28.

Cutter 30 need only swing a distance that is less than the radius thereof, and therefore, the jaw 46 will not interfere with movement of the sleeve 70.

To the end that cable 76 will not become entangled with spring 102, the sleeve 86 is disposed in an offset position with respect to the longitudinal center of stand 10.

It is to be noted also that jaw 42 slides between the arms 44 and cannot rotate therebetween as rod 48 is rotated.

It is thought that the invention and many of its attendant advantages will be understood from

the foregoing description, and it will be apparent that various changes may be made in the form, construction and arrangement of parts without departing from the spirit and scope of the invention or sacrificing all of its material advantages, the form hereinabove described being merely a preferred embodiment thereof.

Having thus described the invention, what is claimed as new and desired to be secured by Letters Patent is:

1. In power saw construction having a swingable cutter head, an elongated member depending from the cutter head at one end thereof and pivotally connected thereto, and a swingable lever for reciprocating the member to swing the cutter head; means joining the lever to the member at selected positions along the length thereof, said means comprising a sleeve circumscribing the member, said member having a row of spaced openings formed therein and extending longitudinally thereof; a spring loaded plunger carried by the sleeve and adapted to be received by any one of said openings; and means pivotally joining the lever and the sleeve.

2. In a power saw construction having a stand, a cutter head swingably mounted on said stand, an elongated member depending from the cutter head at one end thereof and pivotally connected thereto, and a swingable lever mounted on said stand for reciprocating said elongated member to swing said cutter head; a sleeve member circumscribing said elongated member, said sleeve member being slidable on said elongated member and connected to said swingable lever, locking means mounted on said sleeve member for engaging said elongated member to prevent relative movement therebetween, biasing means mounted on said sleeve member for normally urging said locking means into engagement with said elongated member, and lock operating means mounted on said stand and connected to said locking means for moving said locking means to a position out of engagement with said elongated member whereby said swingable lever may be secured by said locking means to said elongated member at selected points along the length thereof.

HAROLD J. WRIGHT.
